Application May 23, 1939, Serial No. 275,166

5 Claims. (Cl. 74—473)

My invention relates to wringers and more particularly to an auxiliary self-operating intermediate mounted engaging and disengaging or shifting mechanism therefor.

With wringers now known, in which an operator may get clothes wrapped around or tangled about the wringer rolls, it is necessary, while operating the wringer to untangle the clothes, to apply or maintain the application of pressure upon the wringer rolls. This requirement is, at times, a very serious handicap in operating the wringer as well as with respect to the removal of the clothes. A further disadvantage in operating any known wringer with clothes tangled about the rolls is that the main operating handle is required to be intermittently manipulated in order to "inch" or slowly move the wringer rolls while the operator untangles the clothes therefrom.

It is, therefore, an object of my invention to provide a mechanism which will permit "inching" or intermittent operation of the rolls to enable an operator to untangle or unwind clothes which have become tangled or wound about the wringer rolls without applying pressure to such rolls, or without having to manipulate the main operating handle.

A further object of my invention is to provide a wringer engaging and disengaging or shifting mechanism, independent of the reversing mechanism, for disconnecting the wringer rolls from the power supply by a light touch from an operator.

A still further object of my invention is to provide an auxiliary intermediate mechanism for permanently connecting the wringer rolls to the power supply through the reversing mechanism when pressure is applied to the wringer rolls and for disconnecting the rolls from the power supply without interfering with the reversing mechanism setting.

Another object of my invention is to provide an auxiliary shifting mechanism for a wringer which is self-operating when actuated by a light touch from an operator or as a result of the actions of the safety release mechanism.

Other objects of my invention will either be pointed out specifically in the course of the following description of one form of apparatus embodying my invention, or will be apparent from such description.

Referring to the accompanying drawings:

Figs. 1 and 2 are side elevational and top plan views, respectively, of a wringer embodying my invention;

Fig. 3 is an enlarged sectional view taken along the line III—III of Fig. 2;

Fig. 4 is an exploded view of the auxiliary shifting or engaging and disengaging mechanism embodying my invention;

Fig. 5 is a sectional view taken along the line V—V of Fig. 3;

Figs. 6, 7 and 8 are sectional views taken along the line VI—VI of Fig. 3 showing the auxiliary mechanism in its various operating and inoperative positions; and

Fig. 9 is a partial side elevational view of the device shown in Fig. 8.

Referring to the accompanying drawings, I show a wringer 12, having a frame 16, a transmission housing 20, a transmission mechanism 24, a lower wringer roller 66, and an auxiliary shifting or engaging and disengaging mechanism 28 positioned intermediate the roll 66 and transmission mechanism 24 and operatively associated therewith.

An interlocking mechanism 26 and an illuminating device 38 is also operatively associated with the wringer 12. This interlocking mechanism is fully described in my copending application Serial No. 275,165, filed May 23, 1939, and the illuminating device 38 is fully described in another copending application Serial No. 275,164, filed May 23, 1939.

The transmission mechanism 24 is located within the housing 20 of wringer 12 and has operatively associated therewith the auxiliary shifting mechanism 28, interlocking device 26 and an operating handle 240. The transmission mechanism 24 comprises a plurality of beveled pinion gears 242 and 244 which are, in this instance (see Fig. 3) rotatably mounted upon and with respect to a power driving shaft 246. The power driving shaft 246 is journalled within suitable bosses 248 and 250 integral with the transmission housing 20, and is operatively associated with a suitable power device, not shown, in any manner desired.

A reversing clutch member 252 is slidably splined to the power driving shaft 246, intermediate the beveled pinion gears 242 and 244. Such clutch member 252 has a grooved-ring portion 254 located in the central portion thereof, and has teeth portions 256 and 258 located on the upper and lower surfaces, respectively, thereof. The teeth portions 256 and 258 of the clutch member 252 cooperate with notched portions 260 and 262, located within the pinion gears 242 and 244, respectively, as the clutch member 252 is moved along the power driven shaft 246 in a man-

ner to be hereinafter described. A beveled gear 264, which is, in this instance, considered a part of the auxiliary mechanism 28, is operatively associated with the pinion gears 242 and 244 and with the wringer roll shaft 186 associated with the lower wringer roll 66, so as to transmit power thereto.

An operating handle 240 rotatably mounted upon the housing 20 operates the reversing clutch member 252 by means of an eccentrically mounted pin 266 rigidly attached thereto in response to rotational movements of the handle, in a well known manner.

The auxiliary shifting or engaging and disengaging mechanism 28, see Figs. 3 to 9, inclusive, comprises the beveled gear 264 which, in this instance, includes an elongated rearwardly extending sleeve portion 270, a lever operating rack 272, a sleeve member 274, a supporting device 276 which is, in this instance, a part of the transmission housing, and a resilient member 278 operatively associated with the sleeve member 274 and the support 276. The beveled gear 264 has, in this instance, the cylindrical sleeve 270 made integral therewith. However, it is to be understood that, if desired, the sleeve portion 270 may be removably attached to the beveled gear 264 in any manner whatsoever.

The rearwardly extending cylindrical sleeve portion 270 has the outside surface thereof machined to form a bearing surface to cooperate with the inside surface of the sleeve 274. The sleeve 274 is mounted within the supporting structure 276 and the sleeve 270 may be mounted therein. The beveled gear 264 and sleeve portion 270 are thus journaled within the sleeve 274 and, accordingly, are free to rotate within such sleeve 274 as an axis. A circular notched portion 280 is cut about the circumference of the sleeve portion 270 to cooperate with the lever operating rack 272 in a manner and for a purpose as hereinafter described.

The lever operating rack 272 comprises two members 310 and 312 which are substantially semi-circular in shape (see Figs. 4 and 6). The members 310 and 312 are formed from sheet metal with upstanding outer walls 314 and 234, and with substantially semi-circularly shaped upstanding inner walls 316 and 236, respectively. Radially outward extending ears 317 may be functionally integral with the inner walls 316 and 236 to enable the two members 310 and 312 to be joined together. These members are joined together, by means of bolts 238 which extend through the ears 317, so as to form substantially a dish-shaped device having a cylindrically-shaped aperture 358 therethrough.

Handles 318 are rigidly attached to the upstanding outer walls 314 and 234 or may be formed integrally therewith. The handles 318 extend radially from the outer walls 314 and 234, and are substantially opposite each other. The handles are of such length to extend outside the wringer 12, through suitable vertically extending elongated apertures 319 located in the housing 20 (see Figs. 1, 2 and 5). Suitable knobs 304 are positioned at the end of the handles 318 to enable an operator to readily operate the mechanism 28, as hereinafter described.

A hardened steel cam-plate or member 292 is attached to the outer surface of the inner upstanding wall 316 of member 310 in any desirable manner. An irregular V-shaped slot 290 is cut within the inner upstanding wall 316 of the op-

erating rack 272 and within the hardened steel cam member 292 (see Figs. 4 and 9). A set screw 286 is attached to the sleeve 274 and cooperates with the V-shaped slot 290 and with an elongated slot 288 in the support 276 to operate the mechanism 28, as hereinafter described.

The central portion of the outer upstanding walls 314 and 234 of the lever operating rack 272 extend somewhat above the remaining portion of the walls, and have inwardly extending curved flanges 360 located at each end (see Figs. 4, 6, 7 and 8). The curved flanges 360 provide a bearing surface for a suitable cam 98, which may rotate the operating rack 272 in either direction to disengage the shifting mechanism simultaneously with the actuation of the safety release mechanism. The cam 98 is attached to and rotates with the pressure shaft 100 which is a part of the wringer safety release and pressure mechanism 31, as is fully described in my copending application, Serial No. 288,311, filed August 4, 1939. The shaft 100 is adapted to rotate in a clockwise direction upon the release of the roll pressure. The cam 98 will thus, through its cooperation with the flanges 360, cause the operating rack 272 to be actuated and to disengage the connection through the mechanism in a manner as hereinafter described and as described and claimed in the above-identified application.

The sleeve member 274 has an outwardly extending flanged portion 282 located at the end thereof and is slidably mounted within the supporting device so that the flange 282 is located farthest from the beveled gear 264 when the sleeve portion thereof is positioned within the sleeve member 274. The resilient member 278 is located about the outside of sleeve 274 and within the supporting device 276. A shoulder 284 in the supporting device 276 cooperates with the resilient member and limits its movement within the supporting device 276. The sleeve member 274 is thus slidably mounted within the support 276 and is biased away from the reversing mechanism or power supplying means by the resilient member 278.

The set screw 286 is threadedly engaged with the sleeve 274 within an aperture 285 and extends into the circular notch 280 in the cylindrical sleeve portion 270 of the beveled gear 264 (see Fig. 5). The set screw 286, rigidly attached to the sleeve 274, in addition to cooperating with beveled gear 264, extends outwardly through the aperture 288 located within the supporting device 276, through the irregularly shaped aperture 290 located within the lever-operating rack 272, and through the hardened steel cam 292 attached to the outside of the lever-operating rack 272. It is, therefore, obvious that the set screw 286 is operatively engaged with the beveled gear 264, sleeve member 274, support 276 and the operating rack 272, and that such set screw will move with the sleeve member 274 and within the slot 288.

When assembling the mechanism 28, the resilient member 278 is positioned over the sleeve 274 substantially as shown in Figs. 3, 4 and 5. The sleeve 274 with the resilient member 270 positioned thereon is then mounted within the supporting device 276 in such a manner that the threaded aperture 285 will be in line with the slot 288 in support 276. The resilient member thus engages the flange 282 and shoulder 284 and biases the sleeve member 274 outwardly.

The beveled gear 264 with the operatively associated cylindrical sleeve portion 270 is then slid 75 within the sleeve member 274 and into such a

position that the circular notch therein will be located substantially below or in line with the threaded apertures 285 in the sleeve member 274 and the slot 288. The set screw 286 may then be inserted within the aperture 288, within the support 276, and tightened down upon the sleeve 274 within threaded aperture 285. The beveled gear 264 and sleeve portion 270 will then be free to rotate within the sleeve member 274, but, due to the cooperative action of the set screw 286, such gear cannot move longitudinally with respect to the sleeve member 274. However, due to the set screw 286 being positioned within the slot 288 in the support 276, the beveled gear 264 and sleeve member 274 can and will move longitudinally together within the confines of the slot 288.

The lever-operating rack 272 may then be positioned about the outside of the supporting device 276 within the housing 20. The irregular V-shaped slot 290 should be positioned in line with the threaded aperture 285 and set screw 286, with such set screw 286 positioned within the irregular V-shaped slot 290. The set screw 286 will then be operatively disposed within the circular notch 280 of the sleeve portion 270, rigidly attached to the sleeve 274, disposed within the longitudinally positioned aperture 288 of the supporting device 276, and also within the irregularly V-shaped slot 290 of the lever-operating rack 272 and of the hardened steel cam 292 attached thereto.

It is to be understood that, as the lever operating rack 272 is positioned about and operatively associated with the support 276, the operating handles, functionally integral therewith, will be positioned through the slots 319 in the wringer housing 20. The operating knobs 304 will thus be positioned outside the wringer with one on either side thereof.

With the auxiliary mechanism 28 assembled in such a manner, it is apparent that the resilient member 278, operatively associated with the flanged portion 282 of the sleeve member 274 and the shoulder portion 284 of the supporting device 276, will bias the sleeve member 274 longitudinally within the supporting device 276. Since the set screw 286 is rigidly attached to the sleeve member 274, and operatively associated with the cylindrical sleeve portion 270 of the beveled gear 264, it is apparent that the beveled gear 264 will be moved longitudinally simultaneously with the movement of the sleeve member 274. However, the longitudinal movement of the beveled gear 264 and the sleeve member 274 will be limited by the dimensions of the slotted aperture 288 located within the supporting device 276. The aperture 288 will likewise prevent the rotation of the sleeve member 274 within the supporting device 276, since due to its shape it will permit only the longitudinal motion of the set screw 286 therein.

When having the auxiliary mechanism 28 associated with the transmission of a wringer, as shown in Fig. 3, the supporting device 276 may be integral with or rigidly attached to the transmission housing or wringer frame. The lever operating rack 272 may then be prevented from longitudinal motion along the supporting device 276 by means of a plurality of ball-headed set screws 300, or the like, operatively associated with the transmission housing 20 and the supporting device 276 through the bosses 302, integral therewith, see Figs. 3 and 4. In addition, the screws 300 provide means for adjusting the

engaged longitudinal position of the gear 264 with respect to the pinions 242 and 244; it being understood that the well known cooperative action between the pinions 242 and 244 with the gear 264 produces a biasing action upon such gear 264 and shifting mechanism 28 towards the right, or away from the pinions.

The ball-headed set screws 300 extend through the transmission housing 20 and into the end of the wringer frame 16. A lock-nut 301 is positioned thereon and tightened upon the frame 16 to lock the screw 300 in any desired position.

It is, therefore, obvious that the set-screws 300 may be adjustably moved into or out of the transmission housing 20 so as to provide means for adjusting the running engagement between the pinions 242 and 244 and the gear 264 while such pinion and gear are in an operating or cooperative engagement. This structure then permits the gear to be adjusted after the wringer has been assembled and provides means for eliminating any noise produced by improper alignment therebetween.

The auxiliary mechanism 28 is operatively associated with the lower wringer roll 66 through the cooperation of a universal coupling 184. The coupling 184 is loosely associated with the mechanism 28 through a cylindrical sleeve bearing 294 and a pin 296. The cylindrical sleeve bearing 294 is located within the free or open end of the cylindrical sleeve 270 operatively associated with the beveled gear 264. The pin 296 may be rigidly attached to the sleeve portion 270 near the open end and along a transverse diameter thereof, and may be inserted through the sleeve bearing 294. A tubular bearing 298 may be positioned about the outside of the pin 296, if desired.

The universal coupling 184, which may be a slotted member loosely attached to the roll shaft 186 by means of a pin 185, may then be mounted within the sleeve bearing 294 with the notched portion thereof cooperating with the pin 296. The rotational energy of the beveled gear 264 will thus be transmitted through the cylindrical sleeve portion 270, the pin 296, the universal coupling 184 and the lower wringer roll shaft 186.

When operating the auxiliary shifting or engaging and disengaging mechanism 28 embodying my invention, the lever operating rack 272 may be manually rotated about the supporting device 276 by means of the operating knobs 304, rigidly attached to the said lever operating rack 272, through the handles 318. The rack 272 may also be rotated automatically, so as to disengage the clutch, in unison with the safety release mechanism through the cooperative action of pressure shaft 100 and by means of the cam 98 engaging the flanges 360. As the lever operating rack 272 is rotated from an engaged position about the supporting device 276 with the beveled gear 264 engaging the pinion gears, the set screw 286, operatively disposed within the aperture 290, will move longitudinally within the aperture 288, due to its cooperative action with the cam 292 and due to the aperture 288 preventing the rotation of the set screw 286.

The aperture 290 is substantially V-shaped (see Fig. 9) and has flattened portions 306 located at each end thereof. Due to the presence of the flattened portion 306 of the aperture 290, the set screw 286, when resting therein, with the beveled gear engaging one of the pinion gears, will hold said beveled gear in such en-

gagement against the longitudinal biasing action of the resilient member 278. However, as the lever operating rack 272 is rotated slightly so that the set screw 286 will be just beyond the flattened portion 306, the resilient member 278 will then force the sleeve member 274 and set screw 286 in a longitudinal manner causing the lever operating rack 272 to rotate. The set screw 286 will thus come to rest in the bottom portion of the V-shaped aperture 290 (see Fig. 9).

As the set screw moves from the flattened portion 306 to the V-shaped portion 308, the sleeve 274 will move a longitudinal distance equal to the length of the aperture 288, which is substantially the longitudinal distance between the flattened portion 306 and the V-shaped portion 308 of the aperture 290. As the set screw and the sleeve member 274 move in such a manner, the beveled gear 264 and the cylindrical sleeve portion 270, due to the cooperating action of the set screw 286 within the circular notched portion 280, will likewise be moved longitudinally within the supporting device 276, a distance equal to the longitudinal movement of the set screw 286.

It is, therefore, obvious that, as the set screw 286, which was located in the flattened portion 306 of the aperture 290 with the clutch in an engaged position, is moved from such position to the apex of the V-shaped portion 308 of the aperture 290, the beveled gear 264 will be moved longitudinally a distance corresponding to such longitudinal movement of the set screw 286, and the lever operating rack will be rotated a distance corresponding to the rotational movement of the cam 292. It is further obvious that with the set screw 286 in the apex portion of the V-shaped groove 290 the beveled gear 264 will be moved to the right or will be disengaged from the pinion gears. In other words the mechanism 28 will be disengaged from the power supply delivered to the wringer rolls from either pinion without affecting the reversing or transmission mechanism setting.

To force the beveled gear 264 back to its original position, it is merely necessary to rotate the lever operating rack in either direction so that the set screw 286 will be forced back to either flattened portion 306. As the lever operating rack 272 is rotated by handle 318, the set screw 286 will be forced along the aperture 290 by means of cam 292 causing the pin 286, since it is prevented from rotation by aperture 288, to move longitudinally within the aperture 288 until it comes to rest upon a flattened portion of the aperture 290. As the lever operating rack 272 is operated in such a manner, the set screw 286 will be moved from the right-hand position, as shown in Fig. 9 to the left-hand position as shown in Fig. 5, where such set screw will be resting along the flattened surface 306. As the set screw 286 is moved longitudinally to the left, the beveled gear 264, through the cooperating action of the set screw 286 within the circular notch 280, will likewise be moved to the left, and will be in a position to engage or will engage the pinions.

It is, therefore, obvious that the lever operating rack 272 may move the beveled gear 264 either from a left-hand or engaged position to a right-hand or disengaged position by merely rotating the lever-operating rack in one direction or the other. It is further obvious that with the lever located in a neutral position, that is, with the beveled gear 264 in its right-hand or

inoperative position, such rack may be moved in either direction to force the beveled gear 264 back into an operative or to its left-hand position.

5 The resilient member 278, which biases the sleeve 274 and set screw 286 to the right and the well known normal thrust action of gear 264, cause the sleeve 274 and sleeve portion 270 to be suddenly moved longitudinally as the lever-operating rack 272 is rotated in either direction, in such a manner that set screw 286 becomes disengaged from the flat portion 306 of slot 290. In other words, the mechanism will be disengaged automatically by resilient member 278 10 when the lever-operating rack is rotated far enough so that the set screw 286 will leave the flat portion 306 of slot 290. By having the length of the flat portion 306 small, it is apparent that the amount of rotation required by rack 272 to 20 operate the shifting mechanism will likewise be small. As an operator rotates the rack 272 by means of a slight touch on either handle 304, rack 272 will permit the set screw 286 to move within the aperture 288 and in turn move the bevel gear 264 longitudinally in the supporting device 276.

It is, therefore, obvious that the mechanism 28 may be operated automatically through the action of the resilient member 278 by means of 30 a light touch of an operator upon handles 204 or by the action of cam 98 on the flanges 360.

Various modifications may be made in the device embodying my invention without departing from the spirit and scope thereof, and I desire, 35 therefore, that only such limitations shall be placed thereon as are imposed by the prior art and the appended claims.

I claim as my invention:

1. A shifting mechanism including a supporting member, a sleeve member rotatably and slidably mounted within said supporting member, said sleeve member having a flanged portion at one end thereof, a resilient member operatively associated with said supporting member and flanged portion of said sleeve member, means comprising said resilient member for moving said sleeve member axially within said supporting member, a driving member rotatively mounted within said sleeve member, and means attached to said sleeve member for moving said driving member axially within said supporting member as said sleeve is moved axially within said supporting member.

2. A shifting mechanism including a supporting member, a sleeve member rotatably and slidably mounted within said supporting member, said sleeve member having a flanged portion at one end thereof, a resilient member operatively associated with said supporting member and flanged portion of said sleeve member, means comprising said resilient member for moving said sleeve member axially within said supporting member, a driving member rotatively mounted within said sleeve member, an operating member rotatably mounted upon said supporting member, and means attached to said sleeve member and operatively associated with said operating member for moving said driving member axially within said supporting member as said sleeve is moved axially within said supporting member.

3. A shifting mechanism including a supporting member, a sleeve member rotatably and slidably mounted within said supporting member having a V-shaped groove located therein, said

sleeve member having a flanged portion at one end thereof, a resilient member operatively associated with said supporting member and flanged portion of said sleeve member, means comprising said resilient member for moving said sleeve member axially within said supporting member, a driving member rotatively mounted within said sleeve member, an operating member rotatably mounted upon said supporting member, and means attached to said sleeve member and operatively associated with said operating member within the V-shaped groove for moving said driving member axially within said supporting member as said sleeve is moved axially within said supporting member.

4. A shifting mechanism including a slotted supporting member, a sleeve member rotatably and slidably mounted within said supporting member, said sleeve member having a flanged portion at one end thereof, a resilient member operatively associated with said supporting member and flanged portion of said sleeve member, means comprising said resilient member for moving said sleeve member axially within said supporting member, a driving member rotatively

mounted within said sleeve member, and means attached to said sleeve member and operatively associated with said slotted supporting member for moving said driving member axially within 5 said supporting member as said sleeve is moved axially within said supporting member.

5. A shifting mechanism including a slotted supporting member, a sleeve member rotatably and slidably mounted within said supporting member, said sleeve member having a flanged portion at one end thereof, a resilient member operatively associated with said supporting member and flanged portion of said sleeve member, means comprising said resilient member for 10 moving said sleeve member axially within said supporting member, a driving member rotatively mounted within said sleeve member, and means attached to said sleeve member and operatively associated with said slotted supporting member for moving said driving member axially within 15 said supporting member as said sleeve is moved axially within said supporting member and for limiting the axial movement of said driving member.

FRANK BRECKENRIDGE.
